(57) **CLAIM**

The ornamental design for a security camera housing, as shown and described.

DESCRIPTION

FIG. 1 is a perspective view of a security camera housing showing my new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a bottom plan view thereof;

FIG. 7 is a top plan view thereof; and,

FIG. 8 is another perspective view thereof, showing the security camera housing in use.

The broken lines shown in the drawings depict unclaimed portions of the article and environmental subject matter that form no part of the claimed design.

1 Claim, 6 Drawing Sheets
